CLAIM

The ornamental design for a housing for a battery terminal connector, as shown and described.

DESCRIPTION

FIG. 1 is a top, front and right side perspective view of a housing for a battery terminal connector showing my new design with the cover thereof in the closed position;

FIG. 2 is a bottom, rear and left side perspective view thereof;

FIG. 3 is a top plan view thereof;

FIG. 4 is a front elevational view thereof;

FIG. 5 is a right side elevational view thereof, the left side elevational view being the mirror image thereof;

FIG. 6 is a rear elevational view thereof;

FIG. 7 is a bottom plan view thereof;

FIG. 8 is a top, rear and left side perspective view of a housing for a battery terminal connector with the cover thereof in the opened position;

FIG. 9 is an inverted bottom, front and right side perspective view of FIG. 8;

FIG. 10 is a top plan view of FIG. 8;

FIG. 11 is a front elevational view of FIG. 8;

FIG. 12 is a right side elevational view of FIG. 8, the left side being a mirror image of that shown;

FIG. 13 is a rear elevational view of FIG. 8; and

FIG. 14 is a bottom plan view of FIG. 8.
